UNITED STATES PATENT OFFICE.

GUSTAVE C. LAMMERS, OF OAKLAND, AND SANFORD BENNETT, OF ALAMEDA, CALIFORNIA.

ELECTROCOSMETIC FACE-MASK.

No. 887,482.

Specification of Letters Patent.

Patented May 12, 1908.

Application filed August 26, 1907. Serial No. 390,153.

To all whom it may concern:

Be it known that we, GUSTAVE C. LAMMERS, of Oakland, Alameda county, California, and SANFORD BENNETT, of Alameda, Alameda county, California, both citizens of the United States, have invented new and useful Improvements in Electrocospetic Face-Masks, of which the following is a specification.

10 Our invention relates to a device for the treatment of the face, and diseases of the skin thereof.

It consists of a rigid mask, molded, and fitting the face, and attachments through 15 which an electric current may be passed.

Referring to the accompanying drawing, for a more complete explanation of our invention, the figure illustrates a mask of this character.

20 Such a mask is constructed as follows: A plaster mold is first taken of the face of the person to which the mask is to be fitted, and after said mold has set, a wax positive facsimile of the face is made by using the plaster 25 or equivalent mask as a negative. The wax positive having been finished is then coated with black lead in the manner usual for preparing surfaces for electro deposit, and being placed in a solution of copper and an elec- 30 trical current passed therethrough, the copper will be deposited, making an exact contour of the face of the person for whom it is intended. We then take this mask and finish it by first plating it with silver to form 35 a proper receiving surface, and upon this a thin plating of gold is deposited. The mask is then ready for use.

Suitable openings may be made in the mask for the eyes, nostrils and mouth, and 40 the mask so made is applied to the face of the wearer, and may be retained thereon by elastic cords connected with its edges, or by other suitable means. Such a mask may be worn at intervals during the day, or applied 45 to the face and retained thereon during the night.

The contact of the metallic surface with the face excites the capillaries, and the nerves and muscles of the face, and produces a 50 stimulating reaction which is very favorable,

and much improves the appearance of the face. In case the face shows eruptions or other skin diseases, this action will tend to remove such disfigurement, and in cases of tan or discoloration, it also exercises a 55 bleaching effect.

The mask A may have a suitable attachment or attachments, as at 2, for wires 3, these wires being connected with any source of electrical energy (not here shown) and 60 from which a current or currents may be passed through the mask and through the surface with which it contacts. The stimulating effect of such electrical currents will be 65 of considerable value in the treatment.

Having thus described our invention, what we claim and desire to secure by Letters Patent is—

1. A device for the treatment of the face and diseases of the skin thereof, said device 70 consisting of a rigid mask molded and fitting the individual face and formed of a material capable of conducting an electrical current to the surface with which the mask contacts.

2. A device for the treatment of the face and diseases of the skin thereof, said device 75 consisting of a rigid metallic mask molded and fitting the face and serving as a conductor of an electrical current to the surface with which the mask contacts.

3. A device for the treatment of the face and diseases of the skin thereof, said device 80 consisting of a rigid metal mask molded upon and accurately fitting the facial surface, and means to apply an electrical current through 85 said contacting surfaces.

4. A face-mask fashioned as a substantial fac-simile of the face to which it is to be fitted, said mask being formed of metal and having a metallic plating, and wires connected to the mask through which an electrical current may be passed.

In testimony whereof we have hereunto set our hands in presence of two subscribing witnesses.

GUSTAVE C. LAMMERS.
SANFORD BENNETT.
